UNITED STATES PATENT OFFICE

HUGH McCABE, OF LAWRENCE, MASSACHUSETTS.

FLANGING MACHINE

1,408,106.

Specification of Letters Patent. Patented Feb. 28, 1922.

Application filed July 3, 1919. Serial No. 308,512.

To all whom it may concern:

Be it known that I, HUGH McCABE, a citizen of the United States, residing at Lawrence, in the county of Essex and State of Massachusetts, have invented certain new and useful Improvements in Flanging Machines; and I do hereby declare the following to be a full, clear, and exact description of the invention, such as will enable others skilled in the art to which it appertains to make and use the same.

This invention relates to flanging machines, and particularly to flanging machines of the type disclosed in the patent to Hugh McCabe No. 1,164,732, dated December 21, 1915, upon which the present invention is an improvement.

When sheet metal is flanged step by step in a machine of the above mentioned type, the incremental flangings cause the upper surface of the sheet to buckle. In my prior patent above mentioned, manually operated means are disclosed for transversely straining the sheet before each increment of the flange is formed, thus counteracting the tendency of the sheet to buckle. In order that the finished sheet may be flat after the flanging operation, the amount to which the sheet is strained in this manner must be regulated more or less carefully so that considerable time and effort is consumed in effecting this regulation. One object of the present invention is to provide power operated mechanism by means of which succeeding portions of the sheet may be automatically strained to the same extent so that the time and effort ordinarily consumed in making this regulation may be eliminated.

The amount to which any particular sheet must be transversely strained, in order that the tendency to buckle may be exactly counteracted depends upon the character of the metal and some sheets which possess the characteristics of springy steel must be strained a considerable amount, so that considerable effort is required on the part of the operator, to turn down the hand wheels and set screws shown in the above mentioned patent.

Another object of the present invention is to provide power operated means whereby such sheets may be strained quickly and with no effort on the part of the operator. A further object of the invention is to improve the construction of flanging machines of the above mentioned type in certain other

details to facilitate the transverse straining of the sheet as will hereinafter appear.

With these objects in view the invention consists in the constructions, arrangements, and combinations of parts hereinafter described and particularly pointed out in the claims, the advantages of which will be obvious to those skilled in the art.

In the drawings illustrating the preferred embodiment of the invention Figure 1 is a side elevation of the improved flanging machine; Fig. 2 is an enlarged end elevation of the power operated straining devices; Fig. 3 an enlarged vertical section of one of the straining devices; and Fig. 4 an enlarged detail of one of the swivel bearing plates.

The improved flanging machine illustrated in the drawings is described as follows: The plate 1, which is to be flanged, is held in a work clamp which comprises an anvil 2 and a clamping block 10. The anvil 2 is lifted by means of a wedge 11 operated by a compressed air cylinder 12 to firmly clamp the work in place. The upper clamp block or member 10 can be swung upwardly by means of a handle 14 so that the work can be readily removed after it is flanged, and for this purpose the brace rods 13 are removably secured to the frame of the clamp-block 10. The flange is bent upon the edge of the plate by means of a bender which comprises a work engaging plate 15 which is mounted upon a segmental bender carrier 16 provided with a segmental gear 17. The segmental gear 17 meshes with a rack 18 which is reciprocated by means of compressed air in the cylinder 19 to impart an angular movement to the bender. The bender is repeatedly oscillated through an angle somewhat more than 30° and the work is fed and clamped until a flange of about 30° is turned over the entire desired length of the plate. Then the bender is shifted forwardly so that the completed flange is bent in a plurality of steps, as clearly described in the McCabe Patent No. 1,030,416. The above mentioned parts with the exceptions hereinafter noted have substantially the same construction and mode of operation as the corresponding parts in the McCabe Patent No. 1,030,416; A mechanism 35 is provided for automatically limiting the movement of the rack 18 whenever its position is changed with relation to the segmental gear 17, so as to control the movements of the bender with relation to the flange and in

this way to permit the bender to be returned free of the flange after it has sprung back, and which is disclosed in and forms the subject matter of another application filed by me on even date herewith, and forms alone no part of the present invention.

The clamping block 10 has a flat work engaging surface and is provided with two laterally extending arms 30 in the end portion of each of which one of the straining devices is secured. Each of the straining devices comprises a supporting casing 49 which screws into the end portion of the arm 30 and which is provided at its upper end with a cap portion screwed thereon and forming a working cylinder 50 for a piston 51. The piston 51 is operated by compressed air admitted to the top of the cylinder 50 through the inlet port 52, swivel coupling 53, flexible hose 54 and pipe 55, connected with a supply of compressed air (not shown). The flow of the compressed air through the pipe 55, flexible hose 54 and coupling 53 is controlled by the manually operated valve 56. The piston 51 is actuated downwardly by compressed air against the compression of a coil spring 57 which embraces a cylindrical guide 58 forming part of the supporting casing 49. The piston 51 is guided in its downward movements by a cylindrical depending portion 59 which fits into the interior of the hollow cylindrical guide 58.

The lower part of the supporting casing 49 is threaded and screws into the supporting arm 30. A hand wheel 60 is secured to the cap member 50 by bolts one of which is shown at 61 and serves to enable the entire device to be screwed down with relation to the supporting arm 30 to effect an initial adjustment of the entire device with relation to the work.

A swivel bearing plate 70 having a substantial bearing area, is mounted on the end 45 of the plunger 71 which is slidably movable within the lower portion of the casing 49. The bearing plate 70 and plunger 71 are held upwardly within the casing 49 by springs 72, embracing swivel guide bolts 50 73, the lower ends of which are mounted in the bearing plate 70. The bolts 73 extend through holes in laterally extended lugs 74, and springs 72 are arranged so that their lower ends rest on the lugs 74, and their 55 upper ends abut nuts 75 secured on the bolts 73. Thus it will be observed that all downward movements of the plunger 71 cause compression of the springs 72, which tend to return the plunger when the downward 60 pressure thereon is removed.

The upper portion of the plunger 71 slides, in the cylindrical hollow guide 58, and the upper end thereof abuts a shoulder 82 in the downwardly depending portion 59 of the 65 piston 51, whereby the downward movement

of the piston 51 is transmitted directly through the plunger 71 to the work. The upper portion of the plunger 71 is provided with a cylindrical recess 62 into which the depending portion 59 of the piston 51 is extended. A groove 63 in the depending portion 59 cooperates with pins 64 in the inner walls of the plunger 71 to raise the plunger 71. The groove 63 is made of sufficient width so as to permit the piston 51 to move upwardly through a certain portion of its upward stroke before the lower wall of the groove is brought into contact with the pins 64 to raise the plunger 71 for a purpose to be described.

The operation of the parts of the straining device is as follows: When compressed air is admitted to the top of the casing 50, the piston 51 is forced downwardly through a definite stroke, thereby compressing the 75 coil spring 57. The plunger 71 is simultaneously moved downwardly by contact of the shoulder 82 with the upper end of the plunger 71. When the piston 51 has reached the end of its downward stroke the plunger 90 is rigidly locked to the supporting casing 49 in a manner to be described, so that if the air pressure above the piston 51 decreases and fluctuates the work will be rigidly maintained in its strained position so long as the 95 air pressure above the piston 51 is sufficient to overcome the compression in the coil spring 57 to maintain the piston in its downward position.

The plunger 71 is provided with a hole 80 100 extended transversely therethrough and in which two steel balls 81 are located being free to roll outwardly and inwardly. The supporting casing 49 is provided with a recess 83, arranged with relation to the transverse hole 80 in the plunger so that when the piston and plunger are at the downward limit of their stroke, the steel balls 81 upon being forced outwardly, fit under the upper end of shoulders 84 of the recess 83, thereby 105 rigidly locking the plunger 71 to the casing 49. In order to control the movements of the steel balls 81, the piston 51 is provided with a hole 90 extended downwardly through the center thereof, in which a plunger 92 110 is slidably received and the end of which is pointed and arranged to project below the bottom surface of the downwardly depending portion 59 of the piston 51. A spring 94 the upper end of which is held by a plug 95 115 screwed into and closing the upper end of the hole 90, serves to yieldingly maintain the plunger 92 in its downward position with relation to the piston 51. A vertically arranged hole 77 in the plunger 71 extends 120 into the transverse hole 80 and is arranged to permit the end of the plunger 92 to be projected into the hole 80 and to thereby force the steel balls 81 to roll outwardly under the shoulders 84 of the recess 83, 130

thereby rigidly locking the plunger 71 to the casing 49.

When the air pressure above the piston 51 is removed, the coil spring 57 causes the piston 51 to start on its upward movement, thereby raising the end of the plunger out of contact with the steel balls 81. By the time that the plunger 92 has been withdrawn from between the steel balls 81, the bottom wall of the groove 63 is brought into engagement with the pin 64 thereby exerting a lifting force upon the plunger 71 by means of which pressure is exerted by the rounded edges of the shoulders 84 upon the steel balls 81, and the latter are rolled inwardly to the interior of the hole 80, thereby permitting the plunger 71 to be lifted upwardly by the piston 51.

Thus it will be observed that in the operation of flanging a metal sheet, the supporting casing 49 is first adjusted to a normal working position by screwing the same downwardly into the supporting arm 30, so that the length of the stroke of the piston 51 will cause the metal sheet to be strained to the desired degree, and in this manner after the initial adjustment has been made, the work may be strained to the same degree when each increment of the flange is turned down, by succeeding operations of the piston 51 without altering the adjustment of the casing 49, thereby eliminating all waste of time and effort.

It will also be observed that the work is positively retained in its strained position during the flanging operation so that counter stresses resulting from the flanging operation, cannot operate to overcome the air pressure above the piston and that these stresses are transmitted, directly to and taken up by the frame of the machine, thus making the construction very economical and practical.

In the above description and in the claims the word "strain" is used in its scientific sense, meaning the deformation which results from a stress. The term "body portion" as herein used designates that portion of the work which constitutes the main body thereof after the flange has been formed. The term is used to distinguish from the flange itself.

While the preferred form of the invention has been illustrated and described, it will be understood that the invention may be embodied in other forms within the scope of the following claims:

1. A flanging machine having, in combination, means for flanging the work, a straining device capable of adjustment toward and from the work, means for adjusting the straining device, and means for operating the straining device without affecting the adjustment thereof.

2. A flanging machine having, in combina-

tion, means for flanging the work, and an adjustable straining device having a work engaging member, means for adjusting the straining device, and means for moving the same without affecting the adjustment of the straining device.

3. A flanging machine having, in combination, means for flanging the work, and a straining device constructed and arranged so that successive portions of the body portion of the work may be automatically strained to substantially the same extent.

4. A flanging machine having, in combination, a work engaging clamp, a straining device mounted on the clamp, and means for flanging the work, said straining device having means whereby successive portions of the body portion of the work may be automatically strained to substantially the same extent.

5. A flanging machine having, in combination, a work engaging clamp and a straining device mounted thereon, the straining device having means whereby successive portions of the body portion of the work may be automatically strained to substantially the same extent and the clamp having provision whereby both the clamp and straining device may be moved into an inoperative position to permit withdrawal of the work after it has been flanged.

6. A flanging machine having, in combination, means for flanging the work, and a straining device having a work engaging member and a pneumatically operated device embodying flexible pneumatic connections for actuating the same to strain the body portion of the work.

7. A flanging machine having, in combination, means for flanging the work, an adjustably mounted straining device for straining the body portion of the work during the flanging operation, means for adjusting the straining device, and means for actuating the straining device through a definite stroke.

8. A flanging machine having, in combination, means for flanging the work, and a straining device for straining the body portion of the work during the flanging operation, said straining device having a work engaging member, means for actuating the same, and means for adjusting the position of said work engaging member and actuating means with relation to the work.

9. A flanging machine having, in combination, means for flanging the work, a straining device having a definite stroke, and means for positively operating the straining device through said definite stroke.

10. A flanging machine having, in combination, means for flanging the work and a straining device provided with a work engaging member, means for actuating the same through a definite stroke, and means

for adjusting the position of the straining device with relation to the work.

11. A flanging machine having, in combination, means for flanging the work, and a straining device having a supporting casing, actuating means movable with relation to the casing having provision for locking the work in its strained position with relation to the supporting casing during the flanging operation.

12. A flanging machine having, in combination, means for flanging the work and a straining device having a supporting casing, power actuated straining means movable with relation to the casing for straining the work and means cooperating therewith for locking the work in its strained position with relation to the casing during the flanging operation.

13. A flanging machine having, in combination, means for flanging the work, and a straining device provided with actuating means for straining the work and having provision whereby the retention of the work in its strained position is accomplished independently of the actuating means.

14. A flanging machine having, in combination, means for flanging the work, and a straining device for straining the body portion of the work during the flanging operation comprising a supporting casing, a fluid actuated piston, and a work engaging plunger actuated thereby.

15. A flanging machine having, in combination, means for flanging the work, and a straining device for straining the body portion of the work during the flanging operation comprising a supporting casing, a fluid actuated piston, a plunger actuated thereby, and a swivel bearing plate mounted on the end of the plunger.

16. A flanging machine provided with a straining device comprising a supporting casing, a fluid actuated piston, a plunger actuated thereby, a swivel bearing plate mounted on the end of the plunger, and means cooperating with the supporting casing for preventing movement of the work from its strained position.

17. A flanging machine having in combination, a bender, a screw-threaded support, a straining device adjustably carried in said support comprising a pneumatically operated work engaging member, for engaging and straining the work and means for retaining the work in its strained position during the flanging operation.

18. A flanging machine having, in combination, a bender, a screw-threaded support, a straining device adjustably carried in said support comprising a pneumatically operated work engaging member, for engaging and straining the body portion of the work during the flanging operation.

HUGH McCABE
